DIGESTER TOP RELIEF SCREEN

Paul Boehm, Rhinelander, Wis.

Application December 14, 1937, Serial No. 179,795

1 Claim. (Cl. 92—7)

This invention relates to a digester screen, the general object of the invention being to provide a screen that can be readily removed for filling of the digester and for cleaning purposes and one that has great strength so that it cannot collapse under digester pressure.

This invention also consists in certain other features of construction and in the combination and arrangement of the several parts, to be hereinafter fully described, illustrated in the accompanying drawings and specifically pointed out in the appended claim.

In describing the invention in detail, reference will be had to the accompanying drawings where-
15 in like characters denote like or corresponding parts throughout the several views, and in which:

Fig. 1 is a top plan view of a digester with the cover removed and the screen in place.

Fig. 2 is a view of the sleeve which is placed in
20 the neck of the digester and carries the screen.

Fig. 3 is a sectional view on line 3—3 of Fig.
1 but with the cover in place.

Fig. 4 is a top view of the sleeve with the screen removed.

25 In these drawings, the numeral 1 indicates the shell of the digester and the numeral 2 the lining thereof. The sleeve is shown at 3 and is provided with the ribs 4 which are embedded in the lining, as shown. The sleeve is provided with a flange 5 at its upper end which extends over the top of the lining and rests on the top of the shell. The upper end of the sleeve has an annular seat 6 therein and the screen or strainer 7 has its flat edge portion seated in this seat. The rest of the strainer or screen is of concavo-convex shape and extends into the top of the sleeve so that the cover 8 can rest flat on the flange of the sleeve and over the screen or strainer without interference from the screen.

As will be seen, the screen or strainer fits loosely in the sleeve so that it can be removed to permit the digester to be filled and to enable the screen to be cleaned. It can be removed without loosening any bolts, screws, nuts or the like. The cover 5 alone holds the screen in place. It has more relieving capacity than any other top relief screen, used in sulphite digesters, and it also has great strength and cannot collapse under digester pressure. It is made of acid resisting material, such 10 as bronze or stainless steel of various types.

It is thought from the foregoing description that the advantages and novel features of the invention will be readily apparent.

It is to be understood that changes may be 15 made in the construction and in the combination and arrangement of the several parts, provided such changes fall within the scope of the appended claim.

Having thus described my invention what I 20 claim and desire to protect by Letters Patent is:

In a digester for cellulous material, a neck having a top face forming a plane surfaced annulus, a sleeve fitted in said neck and having a peripheral flange having its under side forming 25 a plane surface and resting on said top face, said sleeve having a rabbet extending outwardly from the inner surface of the sleeve at the top thereof, a concave top relief strainer having a peripheral flange fitting in said rabbet with the upper surface of the flange flush with the upper surface of the sleeve flange, said flush flanges forming an annular plane surface, and a cover plate resting on said flanges and having a plane under surface 30 whereby the cover plate has the combined functions of closing the device, of bearing downwardly on the sleeve flange in direct contact therewith and of holding the strainer in place.

PAUL BOEHM.
